UNITED STATES PATENT OFFICE.

CONSTANT LARIDON, OF DETROIT, MICHIGAN.

RAILWAY AUTOMATIC SWITCH.

1,304,329.

Specification of Letters Patent. Patented May 20, 1919.

Application filed February 17, 1919. Serial No. 277,387.

To all whom it may concern:

Be it known that I, CONSTANT LARIDON, a subject of the King of Belgium, residing at Detroit, county of Wayne, State of Michigan, have invented a new and useful Improvement in Railway Automatic Switches, of which the following is a specification.

This invention relates to automatic street car switches of a mechanical type adapted to be thrown by devices on the car.

Of course devices of this character are not broadly new but the improvement herein claimed is thought to be a considerable advance over previous devices in simplicity of construction and mechanical design. It embodies a snapping action to either position after the throwing of the switch has been initiated by the proper devices. This snapping action not only insures the reliable operation of the switch every time but also serves to lock the cross-over section in either of the selected positions.

The devices used on the ground and car are both simple and of such a character as to obstruct neither the ground nor the car in any serious manner. The advantages, functions, etc., can be better explained after a detailed description has been had.

In the drawings,—

Fig. 1 is a plan view of a track and a branch line showing the switch devices which are upon the ground.

Fig. 2 is a fragmentary side elevation of a street car partly in section, showing the switch devices used on the car and showing a section through the bed of the track and the switch devices.

Fig. 3 is a small plan view of the car truck showing the trip arms and rock shaft.

Fig. 4 is an enlarged longitudinal section of the track bed through the box containing the switch devices.

Fig. 5 is an enlarged plan view of the switch box partly in a section taken on the line 5—5 of Fig. 4.

Fig. 6 is a longitudinal section of one of the trip arms.

a designates the main line of track which branches off to the left of Fig. 1 into a curved stretch. The cross-over from the main run a to the curved stretch of track b is accomplished by a pair of pivoted cross-over rails, one from the straight line and one from the curved line of track. This, of course, could be built in the customary way of having both the cross-over rails sections of the

curved line of track. These two swinging cross-over rails are connected by the cross bar c.

The automatic switch is of extreme simplicity. It involves simply a four-armed actuator d, all the arms being substantially of the same length, radially disposed and at equally distant points about the center. One arm is pivoted to the cross bar c; the opposite arm forms part of a pair of toggle arms designated e. The actuator d is pivoted fixedly at the center so the toggle arms are of single action principle, that is, they are fixed at one end and spread at the opposite end where they connect with a plunger stem enlarging into a piston f guided in a cylinder g against the resistance of the spring h. At the ends of the two remaining and opposed arms of the actuator are connected the draw links i.

Obviously when the draw link that stands advanced is pulled, it tends to rotate the actuator upon its center until the dead center line of the toggle arms e is reached. Thereupon the toggle arms and actuator, and the draw links, are snapped into their final position by the exertion of the spring h expanding after the center line has been passed. This is the characteristic action of a spring-resisted toggle thrown by the center line. This, of course, swings the cross bar c and the two cross-over arms quickly into the final position, either one of which is selected. The great usefulness of this arrangement is that it serves to positively complete the switch action although the action of the trip device which has initiated this switch action may not be as positive as might be desired, due to accident, improper calculation of distance, or other causes. A very useful feature of this arrangement is that it locks the cross-over in the selected position or substantially locks it for all intents and purposes. The strength of the spring is sufficient to prevent the cross-over accidentally swinging back from the selected position. There is absolutely no danger of the car splitting the switch, which is quite a common occurrence at ordinary switches.

The devices that have just been referred to are located in a slight depression in the bed of the track and are inclosed in a switch box h' which may be given suitable covering to in the best possible way exclude water and dirt. Through recesses in the top of this switch box are a pair of bell crank

levers *j* swinging in vertical planes, pivoted on a cross rod *k*. These bell crank levers have broad faces which look very much like the pedals used on old-fashioned organs

5 as far as contour is concerned. These pedals are shielded at each side by sloping side rails *m* which have a gradual convexity reaching the maximum height of about that of the pedal opposite the point of the pedals' maximum height. Consequently when 10 a vehicle passes over this cover plate and over these convex rails *m*, it will not disturb the pedals.

The tripping of the switch is effected by 15 the trip arms *n* and *o* set fixedly on the rock shaft *p* carried on the truck of the car. Each arm comprises a cylinder *q*, the plunger member *r*, yoking a roller *s* and a spring *t* for yieldingly projecting the plunger. This construction is in case the roller 20 accidentally strikes an obstruction the trip devices will not be injured but have a capacity for considerable telescoping movement to pass over the obstruction. The rock shaft is connected by a crank and a link *v* with a hand lever *w* which may be located in the vestibule of the car. This is provided with a notched segment *x* over which the lever swings and in the notches of which 25 it may be engaged by the detent *y* to give three positions; the central, neutral position, the forward, or the rear position.

By selecting the forward position the motorman knows that he will trip the switch 30 pedal at the right if that needs tripping, by reason of the position of the cross-over, and by selecting the rear position the motorman knows that the cross-over will be so placed that it will trip the left hand pedal lever.

35 40 The automatic switch can be disconnected very easily by simply taking out the screw *x* and then the cross-over is perfectly free to be thrown by a pinch bar, or for that matter, it can always be so thrown if the 45 switch is in working condition.

What I claim is:

1. An automatic switch, having in combination with a swinging cross-over, means on the car and in connection with the cross-over for initiating the swing of the cross-over in either one of two selected positions, and means for assisting in completing the final portion of such swing and holding it in the selected position.

50 55 2. An automatic switch, having in combination with a swinging cross-over, means on the car and in connection with the cross-over for initiating the swing of the cross-over to either of two positions, and yield-

ing means for assisting in finishing the 60 swing of the cross-over to either one of the selected positions and holding it in such selected position.

3. An automatic switch, having in combination with a swinging cross-over, means 65 in connection with the cross-over and on the car for initiating the swing of the cross-over to either of two selected positions, and mechanism including a spring operating on the principle of throwing over a dead center line for assisting in completing the swing 70 of the cross-over and holding the cross-over in the selected position.

4. An automatic switch, having in combination with a swinging cross-over, means 75 on the car and in connection with the cross-over for initiating the swing of the cross-over to either of two selected positions, a pair of toggle arms whose movement past their center line is resisted by a spring and 80 connected to the cross-over for assisting in finishing the swing of the cross-over and holding the cross-over in selected position.

5. An automatic switch, having in combination with a swinging cross-over, means 85 on the car and in connection with the cross-over for initiating the swing of the cross-over to either of the two selectable positions, a cross bar for the cross-over, a lever connected thereto and fixedly pivoted to act as 90 one of a pair of toggle arms, a second lever acting as the second member of the toggle, and a spring for resisting these two levers passing their dead center line whereby this toggle arm and spring serve to assist in 95 completing the movement of the cross-over and hold the cross-over in one of the selectable positions.

6. An automatic switch, having in combination with a swinging cross-over, an actuator, 100 draft means connected with each side of the actuator which is pivoted at its center to swing the cross-over from one to the other of two selectable positions, pedals above the bed of the track connected with 105 the draft means and alternately raised and lowered according to the action of the actuator, and a pair of toggle arms in connection with the actuator having a spring 110 resisting their movement past a dead center, said toggle arms serving to aid the action of the cross-over after they have passed their center and holding the cross-over in its selected position.

In witness whereof I have hereunto set 115 my hand on the 7th day of February, 1919.

CONSTANT LARIDON.
